WILLIAM E. PRALL, OF WASHINGTON, DISTRICT OF COLUMBIA, ASSIGNOR TO HIMSELF AND A. C. RAND, OF NEW YORK CITY.

Letters Patent No. 92,357, dated July 6, 1869.

IMPROVEMENT IN STEAM WATER-ELEVATOR

The Schedule referred to in these Letters Patent and making part of the same.

To all whom it may concern:

Be it known that I, WILLIAM E. PRALL, of Washington, in the county of Washington, and District of Columbia, have invented a new and useful Improvement in Water-Elevators; and I do hereby declare that the following is a full, clear, and exact description of the same, reference being had to the annexed drawings, making part of this specification, in which—

Figure 1 is an elevation of my improved elevator, and

Figure 2 is a vertical sectional elevation of the same.

Corresponding letters, in both figures, refer to corresponding parts.

This invention relates to that class of devices which elevates water by means of steam, which is generated within the device for raising the water, and which is then condensed therein, for the purpose of forming a vacuum for permitting the influx of more water, and it is designed as an improvement on the one for which Letters Patent were granted to me on the 21st day of April, 1868, it consisting of a new combination and arrangement of the parts of which it is composed, as will be more fully described hereinafter.

A, in the drawings, represents a vessel, into which the water enters from the well or reservoir, when the device is in operation.

To the lower portion of this vessel, there is to be secured a pipe or conduit, A¹, which may be a constituent part of such vessel, or it may be a separate piece, and be secured thereto in any suitable manner.

This pipe or conduit extends downward for some distance, when it is to be bent or curved, as shown in the drawings, and is to extend upward for a suitable distance, and then outward in a horizontal direction, and terminate in a somewhat enlarged portion A².

It will be apparent, that each of the parts marked A A¹ A², may be cast or formed of separate pieces, and screwed or otherwise secured together, but, as a matter of convenience, I prefer to cast or form them in one piece.

That portion of the pipe or conduit A¹ above referred to, I designate and propose to use as the steam-generator, it being supplied with water, as will be more fully described hereafter.

The location and dimensions of this generator should be such that the amount of water contained therein, will always be less than the amount which the vertical arm of the pipe A¹ contains, so that as the water is expelled from the generator, the hot water will not be forced out of such pipe.

B represents an induction-pipe, which is to be secured to the lower portion of the vessel A, and is to extend down into the well or other source of supply, and is to be supplied at its lower end with an ordinary or any suitable check-valve.

This pipe may be secured to the vessel in any of the well-known ways, the most convenient being that of a nut upon its end, which shall screw upon a projection upon the vessel.

C represents the water-discharge pipe, which is to be secured to the upper portion of vessel A, and is to have within it, at a short distance above such vessel, a check-valve, opening upward or outward, for preventing the return of the water from such pipe to the vessel. This pipe is to be of any length required, to carry the water to the desired location, and may be bent or otherwise arranged with reference to that end.

D represents a bent pipe, one end of which is secured to the upper portion of vessel A, above which it rises vertically for a considerable distance, when it is bent or otherwise caused to turn downward, in which direction it extends in a line nearly parallel with the upwardly-projecting portion, and until it reaches the vertical portion of the pipe or conduit A¹, to which it is joined, and with which it is made to communicate, for a purpose which will shortly be explained.

E represents a pipe, which is to be attached to the upper surface of the steam-generator, from which point it is to extend inward toward the pipe D, but before reaching which it is to be bent downward to a point somewhat below the lower portion of the generator, or it may be to any point to which it is desired to discharge the water from the generator, as it is apparent that by the location of this pipe, the quantity of water discharged may be regulated, when it is to be so bent or formed as to rise vertically alongside of pipe D and enter the same, or communicate therewith at a point somewhat above the upper surface of the steam-generator.

F represents a pipe, which communicates with the discharge-pipe C, at a point above the check-valve a, and which extends across, and is connected to, and communicates with the downwardly-projecting portion of pipe D.

Upon that end of pipe F, which enters pipe D, there is to be placed a small nozzle, which extends upward for a short distance within pipe D, which is for the purpose of introducing a jet of cold water from the discharge-pipe C into the condenser, which consists of the upper portion of the bent pipe D.

The operation of my improved water-elevator is as follows:

The parts, having been constructed as above described, and arranged as shown in the drawings, are to be filled with water up to or about to a level with the top of the vessel A, when the steam-generator, or that portion marked A², is to be placed in contact with a fire prepared for that purpose, when steam will be generated therein, which steam will force the water from A¹ into the vessel A, and from thence through the discharge-pipe C to the desired locality.

It is apparent, however, that not all of the water contained in the pipe A¹ will be discharged, for the reason that so soon as the water has been driven below the lowest point in pipe E, the steam which had previously acted upon the water, will be allowed to pass through pipe E into D, in the upper portion of which it will be condensed by the jet of water, which will enter through pipe F.

The condensation of the steam, as above described, will, of course, produce a vacuum in the pipe D, the effect of which will be to permit water to flow through the pipe B into vessel A, and thus refill the same, and also refill the generator with the hot water which was retained within the pipe A¹, so that it will be seen that the generator is, after the first discharge of water, always refilled with hot water, and that thus a great economy of fuel is produced, especially as the steam used, in raising the water, is condensed and returned to the generator.

The office of the pipe E is to allow any steam, which may be in the generator, to escape after it has driven the water below the lowest point in such pipe, and thus permit the generator to refill with the water previously contained therein, as it is apparent that such water will not be expelled from the pipe A¹, but only the cold water, which was contained in the opposite leg of the pipe to the one into which the hot water is forced from the generator.

In addition to the function of a condenser, described as being performed by the upper portion of tube D, it will be seen that it acts as an air-chamber, the air contained therein pressing equally upon the two columns of water, and thus preventing the water, in either col-

umn or portion of the pipes, from passing to the other column or portion, which would sometimes be the case were it not for the air in the pipe D.

As a further safeguard against the passage of the water from one portion of the pipe to the other, I propose to use perforated diaphragms in the pipes, one in each portion thereof, so that in the event of any sudden commotion in the water within the device, caused by the closing of the valve, or the generation of an unusual quantity of steam, the tendency to such passage of the water will be still further checked.

Having thus fully described my invention, What I claim, and desire to secure by Letters Patent, is—

1. The combination of the reservoir A, the generator A², and connecting-pipe A¹, constructed and arranged substantially as set forth.
2. The arrangement of the reservoir A, the pipe D, and the pipe or conduit A¹, substantially as shown and described.
3. The combination of pipe D, generator A², and the pipe E, substantially as shown and described.
4. The combination and arrangement of the discharge-pipe C, jet-pipe F, and pipe D, substantially as shown and described.

In testimony whereof, I have signed my name to this specification, in the presence of two subscribing witnesses.

W. E. PRALL.
